CATCH

Bruno C. Roehrl, Erie, Pa., assignor to National
Organ Supply Company, Erie, Pa., a corpora-
tion of Pennsylvania

Application April 1, 1947, Serial No. 738,539

5 Claims. (Cl. 292—219)

1

This invention is a spring catch. One advantage is the possibility of recessing the catch into an edge of a case. Other objects and advantages appear in the specification and claims.

In the drawing Fig. 1 is a section through the catch applied to a case, Fig. 2 is a perspective of the case partly in section, Fig. 3 is a perspective of the catch, and Fig. 4 is a top edge view.

1 and 2 indicate mating parts of a case hinged at one end (not shown) and held closed by a catch 3 having its outer surface conforming with and constituting a smooth continuation of the edge contour of the case. The catch is hollow having end walls 4 received in a notch 5 in the casing part 2 and having outwardly flaring end walls 6 received in a notch 7 in the casing part 1. Projecting from the walls 6 are flanges 8 loosely received in slots 9. A retaining lip 10 at the front of the catch is held against shoulder 11 in the casing part 2 by a wire spring 12 having its center received in a hook 13 on the casing part 1 and its ends received in holes 14 in the end walls 6. The length of the spring is substantially equal to the width of the catch at the holes 14. After the catch is slid into place from the outside of the casing part 1, the center of the spring is pulled forward and downward into engagement with the hook 13. This bows the spring placing it under the desired tension. The thickness of the walls 6 is such that the ends of the spring remain in the holes 14. The force exerted by the spring urges the catch forward against ribs 15 which provide stops. The direction of the spring force is partly downward and partly forward, the greater force being forward. As the case is closed, the upper edge of the part 2 engages a cam surface 16 on the lip 10 lifting the front edge of the catch until the lip 10 snaps down onto the shoulder 11. The force exerted on the cam surface 16 is partly upward and partly rearward. Because the rearward force exerted on the cam surface is less than the forward force exerted by the spring, the catch pivots about the edge 11, the necessary limited pivotal movement being permitted by the clearance between the flanges 8 and the slots. Limiting the pivotal movement of the catch prevents overstressing of the spring. The necessary upward force to release the catch may be applied to a rib 18 at the front end of the cam surface 16. This makes only a slight variation in the contour of the case—just enough to provide a gripping surface.

What I claim as new is:

1. In a case having separable parts with mat-
ing edges, aligned notches transverse to the edges,

2

a latch member received in the notches, guides mounting the latch member on one of the parts for sliding movement toward the other part, said guides having lost motion permitting limited pivotal movement of the latch, spring means urging the latch member downward and forward toward the other part, a stop limiting the forward movement of the latch, and cam surfaces on the latch and the other part exerting opposing forces on the latch as the case is closed less than the forward and greater than the downward force of the spring means.

2. In a case having separable parts with mat-
ing edges, aligned notches transverse to the
edges, a hollow latch member received in the
notches, guides mounting the latch member on
one of the parts for sliding movement toward
the other part, said guides having lost motion
permitting limited pivotal movement of the latch,
a spring within and extending across and hav-
ing its ends anchored in the latch member, and
an abutment in said one part downward and
forward of the ends of the spring engaging the
center of the spring, said abutment being posi-
tioned so the spring exerts a greater force urg-
ing the latch member forward and a lesser force
urging the latch member downward toward the
other casing part.

3. In a case having separable parts with mat-
ing edges, aligned notches transverse to the
edges, a latch member received in the notches,
slots in the ends of the notch in one of the parts,
projections on the latch member loosely received
in the slots permitting sliding and pivotal move-
ment of the latch in the slots, and spring means
exerting a greater force urging the latch mem-
ber forward and a lesser force urging the latch
member downward toward the other part.

4. In a case having separable parts with mat-
ing edges, a notch in one of the parts transverse
to its edge, a latch member received in the notch
and cooperating with the other part to hold the
edges together, guides mounting the latch mem-
ber on said one part for sliding movement to-
ward the other part, said guides having lost motion
permitting limited pivotal movement of the
latch, spring means urging the latch member
downward and forward toward the other part,
a stop limiting the forward movement of the
latch, and cam surfaces on the latch and the
other part exerting opposing forces on the latch
as the case is closed less than the forward and
greater than the downward force of the spring
means.

5. In a case having separable parts with mat-

ing edges, a notch in one of the parts transverse to its edge, a hollow latch member received in the notch and cooperating with the other part to hold the edges together, guides mounting the latch member on said one part for sliding movement toward the other part, said guides having lost motion permitting limited pivotal movement of the latch, a spring within and extending across and having its ends anchored in the latch member, and an abutment in said one part downward and forward of the ends of the spring engaging the center of the spring, said abutment being positioned so the spring exerts a greater force

urging the latch member forward and a lesser force urging the latch member downward toward the other casing part.
